Attorney:

UNITED STATES PATENT OFFICE.

GROVER PERRY, OF CHICAGO, ILLINOIS.

PORTABLE BOOKCASE.

1,329,429.

Specification of Letters Patent.

Patented Feb. 3, 1920.

Application filed November 17, 1917. Serial No. 202,456.

To all whom it may concern:

Be it known that I, GROVER PERRY, a citizen of the United States of America, and resident of Chicago, Cook county, Illinois, 5 have invented certain new and useful Improvements in Portable Bookcases, of which the following is a specification.

My invention relates in general to a portable book case and more specifically to a 10 combined traveling case and book-rack or stand upon which books and other materials may be mounted.

Among the objects of my invention are to provide a compact and easily handled portable case for use in carrying books and one which, when opened, forms a stand or rack upon which the books are mounted and from which they need not be removed in order to open and study the same.

20 My invention is especially adapted for use by Sunday school teachers, Christian Science teachers, or any others who may desire to carry a set of books and writing material while traveling and who may desire 25 to consult the books at frequent intervals and at times when a table or stand is not accessible upon which to rest the same.

Other features and objects of my invention will be more clearly understood by referring to the accompanying drawings and 30 specification in which drawings:—

Figure 1 shows the case when closed and in carrying condition.

Fig. 2 shows the case when opened out 35 flat with the books and other materials in their places.

Fig. 3 shows the case as it appears when set up as a stand or rack and with the books removed to more clearly show the construction 40 of the same.

Referring now to Fig. 1 I have shown the case in a closed or carrying condition with the flaps all closed and fastened and showing a handle 2 which is firmly secured to the flap 45 3 by means of a pair of straps 4 and 5. The flap 3 is fastened by means of a pair of snap fasteners 6 and 7.

In Fig. 2 I have shown the case when 50 opened out flat with the books open. In this figure it will be seen that the case when opened out forms a flat strip of leather which is stitched at various points in order to form joints at which the case may readily be folded. It comprises the front piece 8 having 55 a pair of flaps on each side thereof, a back piece 18 having a flap 3, comprising the

folding sections *a* and *b* on the upper side thereof and a portion 19 which when the case is folded forms the base thereof. The front piece 8 has secured thereto a pair of 60 pockets 9 and 10. These pockets are made preferably of one piece of leather or other material which is stitched down in such a manner as to leave a pair of openings one on each side of the front 8 into which the 65 front and back covers respectively of a pair of books 14 and 15 may be inserted. These two openings are represented by the full lines 10^a and 11. A pair of flaps or side pieces 12 and 13 are attached to the front 70 piece 8 one on each side thereof, which, when the books 14 and 15 are closed, may be folded over to form the sides of the case as shown in Fig. 1. A pair of snap fasteners 16 and 17 are provided in the flaps 12 and 13 75 so that, when the case is closed, the back piece 18 may be firmly secured to the front piece by means of the snaps 16 and 17 and the co-operating snaps 20 and 21. The books 14 and 15 are indicated by the heavily dotted 80 lines and shown in open position. The section 19 forms the base or bottom of the case and is made so as to fold on the lines 22. The back piece 18 has a pocket 23 on the left hand half thereof which is formed in 85 the same manner as the pockets 9 and 10, and a pair of pockets 24 and 25 on the right hand half thereof. The pocket 23 is the larger of the three and is adapted to have the front cover of a quarterly or pamphlet 90 inserted therein. The pocket 25 is of smaller size and may be used to carry visiting or business cards. The pocket 24 is larger than the pocket 25 and may be used for carrying memorandum paper or notes of any sort. 95 This pocket 25 is provided with a flap 26 for inclosing the opening thereof, which may also be used to hold open the quarterly which is inserted in the pocket 23. Just above the pockets 23 and 24 I have provided 100 a small strip 27, attached to the piece 18 at two edges and having an opening or loop for carrying a pen or pencil. Below the pencil holder 27 is attached a strap or cord 28 having a ring 29 attached to the lower 105 end thereof. This ring 29 is adapted to be fastened over a hook 30 on the front piece 8. This strap is for holding the back piece 18 in a raised position so that, as shown in Fig. 3 with the ring 29 over the hook 30, the piece 110 18 stands at an angle of about 125° from the piece 8 and therefore holds the quarterly in

a position easily accessible while reading the books 14 and 15. In Fig. 3 the books 14 and 15 have been left out of the drawing so that the pockets 9 and 10 and the flaps 12 and 13 5 may be more clearly seen. Although the carrying strap 2 is shown only in Fig. 1 it will be understood that this strap is located on the opposite side of the section 3 in Figs. 2 and 3. This case may be made of any suitable 10 material preferably of morocco leather. The pockets may also be made of any desired material and in order to make the case stiffer and more easily handled each section such as the sections 3, 8, 12, 13, 18, etc., may be 15 lined with leather and have a strip of case board or other stiffening material slightly smaller than each section incased in said lining and beveled at the edges, leaving enough room at each joint so that the flaps may be 20 folded easily.

It will be seen therefore that I have invented a very useful and novel book case which is adapted for many uses, and which when open forms a very handy and complete 25 desk or stand for study while *en route* and which when closed, folds up into a compact and easily handled case which is but a very little larger in size than the actual contents thereof.

Having described my invention, what I 30 claim as new and desire to have protected by Letters Patent will be pointed out in the appended claims.

What I claim as my invention is:

1. An article of manufacture, consisting 35 of a plate with a pair of pockets facing in reverse directions, whereby a pair of books may be held in position one with one cover in one pocket and the other with the opposite 40 cover in the other pocket, and wings or flaps attached to the edges of said plate arranged to fold over the books while in position, to inclose them in a case like inclosure, means for latching said wings in position 45 when folded, a pocket in one of said wings for receiving one side of the cover of another book, whereby such book may be held in position and whereby it may be opened while so held, and another pocket in said 50 wing having a flap for holding said last mentioned book.

2. As an article of manufacture a combined traveling case and desk having receptacles for holding a plurality of books and writing material, whereby when said case is 55 opened it forms a rack or stand, on which said books may be opened without removing them from said receptacles, means for closing, locking and carrying said case, said desk comprising a horizontal plate for holding a pair of books and another plate for holding another book in a raised position and interlocking flaps for maintaining said case in locked condition.

3. As an article of manufacture a combined traveling case and desk having receptacles for holding a plurality of books and writing material, whereby when said case is opened it forms a rack or stand, on which said books may be opened without removing 60 them from said receptacles, means for closing, locking and carrying said case, said desk comprising a horizontal plate for holding a pair of books, another plate for holding another book in a raised position, interlocking flaps for maintaining said case in 65 locked condition, and a flexible link for holding said last plate in raised position.

4. An article of manufacture consisting 70 of a pair of plates, a plurality of pockets in 80 each of said plates for holding books and like material, the pockets in one of said plates being reversed one for holding the back cover of one book and another for holding the front cover of another book, where- 85 by said books may be opened without removing them from said pockets, one of the pockets in said other plate having an opening for holding the front cover of a book and another of the pockets having a flap for 90 holding said last book open, means for holding one of said plates in a raised position relative to the other plates and means for folding said plates to inclose said books and means comprising a plurality of flaps and 95 fasteners for locking said plates together to form a case and means for carrying said case.

Signed by me at Chicago, Cook county, Illinois, this 10th day of November, 1917. 100

GROVER PERRY.
